UNITED STATES PATENT OFFICE.

CHARLES H. HAESLER, OF CHICAGO, ILLINOIS.

PNEUMATIC HAMMER.

1,372,348.

Specification of Letters Patent. Patented Mar. 22, 1921.

Application filed August 15, 1916. Serial No. 114,948.

To all whom it may concern:

Be it known that I, CHARLES H. HAESLER, a citizen of the United States, residing in the city of Chicago, county of Cook, State of Illinois, have invented a new and useful Pneumatic Hammer, of which the following is a specification.

In the use of pneumatic hammers wherein a reciprocating piston is adapted to impact against a working tool, accidents frequently occur due to the accidental discharge of the piston from the forward end of the tool cylinder. In view of these numerous accidents, which have arisen from this cause, many of the States in this country have passed laws rendering it compulsory in devices of this character to employ some means to prevent the accidental discharge of the piston from the cylinder or barrel of the tool. The cost of operation is also increased, since the piston is sometimes injured and in many cases, such as structural operation and bridge building, the working tool or piston or both are lost and it is necessary to replace them.

It is therefore also desirable to employ means to prevent the piston and also the working tool, such as for example a rivet set, from being forcibly ejected from the cylinder, and to the above ends, my present invention consists of novel means for preventing the accidental removal of the rivet set and the piston from the barrel of the working tool.

It further consists of novel means for retaining the working tool in assembled position, whereby it may be readily inserted and removed when desired, and wherein if the pneumatic tool is not held to its work, the shank of the rivet set will be moved forwardly a sufficient distance to be out of the path of the piston, so that the latter cannot impact thereagainst.

It further consists of a novel construction of a coupling sleeve by which the working tool is movably carried, and novel means for securing such coupling sleeve with respect to the barrel or cylinder of the pneumatic tool.

It further consists of a novel construction of a working tool and novel means co-operating therewith, whereby the accidental removal of the working tool from the coupling sleeve is prevented.

It further consists of a novel construction of a coupling sleeve adapted to be removably connected with the barrel of the tool and

having a chamber in advance of the forward end of the barrel in which is adapted to reciprocate a split ring which is interlocked with the shank of the working tool.

Other novel features of construction and advantage will hereinafter more clearly appear in the detailed description.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation, partly in section, of a pneumatic tool in conjunction with which a retaining device for the working tool, embodying my invention, is employed.

Fig. 2 represents a sectional view, the section being taken on line 2—2 of Fig. 1.

Fig. 3 represents a sectional view, the section being taken on line 3—3 of Fig. 1.

Similar numerals of reference indicate corresponding parts in the figures.

Referring to the drawings:

1 designates a pneumatic tool of any desired or conventional type, which is provided with a barrel 2 having a piston chamber 3 in which is adapted to reciprocate a piston 4. The piston 4 consists, in the present instance, of a cylindrical bolt having a forward extension or striker 5 of reduced diameter which is adapted to pass through an aperture 6 in the barrel to impart its blows against the end of the shank 7 of a working tool 8, which for purpose of illustration is illustrated as comprising a rivet set.

The aperture 6 is of less diameter than the piston chamber 3, thereby forming a shoulder 9, so that the piston 4 cannot be ejected from the front end of the barrel, but only from the rear end of the barrel after the handle 10 has been removed. The piston 4 is reciprocated in the usual manner by alternately passing motive fluid, such as for example, compressed air, to opposite ends of the piston 4 to effect its reciprocations.

The forward end of the barrel 2, in the

present instance, is of reduced diameter, as indicated at 11, in order to receive the rearward extension 12 of a coupling sleeve 13, the outer diameter of which is preferably 5 the same as that of the barrel 2. The coupling sleeve 13 is provided with an intermediate portion 14 of less internal diameter than the chamber of the rearward extension 12 and the forward end of the coupling sleeve has a solid portion 15, which 10 is apertured as at 16, in order to receive the shank 7 which fits therein and also in a recess 17 in the end of the barrel 2, said recess 17 communicating with the aperture 6.

15 The shank 7 of the working tool is provided with means to interlock with a split ring 18 and in order to illustrate one manner of accomplishing this result, I have shown the shank 7 as provided with an annular groove 19 to receive such split ring. The differential bore of the coupling sleeve 13 forms a shoulder 20 against which the end of the barrel 2 preferably engages and when the parts are assembled, a chamber 21 20 is formed in which the split ring 18 may reciprocate.

25

22 designates fastening devices, such as for example, screws which extend through the rearward extension 12 of the coupling 30 sleeve 13 and which are in threaded engagement with the barrel 2, as will be readily apparent from an inspection of Fig. 2.

23 designates a split band having a groove 35 24 at its inner periphery, said band being adapted to be moved over the outer ends of the fastening devices 22, so as to prevent their loosening. It will be seen that when the band 23 is removed, the fastening devices 22 may be loosened, so that the coupling sleeve 13 may be readily removed 40 from the barrel 2.

In the operation, the motive fluid admitted to the rear end of the fluid pressure operated tool, causes the piston to be advanced 45 in the well-known manner and the motive fluid passing from the forward end of the piston chamber 3 through the port or ports 25 and acting against a shoulder 26 on the piston, causes it to be returned to its initial position at the rear end of the barrel. When the piston reaches the end of its forward stroke, the forward extension or striker 5 impacts against the end of the shank 7 of the working tool 8. In case the 50 pneumatic tool is not held to the work, it will be seen that this will cause the working tool to move forwardly so that the end of the shank 7 is out of the path of the piston. The split ring 18 which is interlocked 55 with the shank 7 will engage the shoulder 26 and prevent the working tool from being accidentally ejected from the barrel and the coupling sleeve.

When it is desired to remove the working 60 tool, it is simply necessary to draw the same

outwardly in a proper manner, so that the split ring 18 will become disengaged from its groove 19 and the working tool may then be readily removed. It will be seen that when a working tool is inserted in position, 70 its shank will pass through the aperture 16 and through the split ring 18 which will abut against the forward end of the barrel 2 so that the shank 7 will pass therethrough and the split ring will interlock with the 75 groove 19 of the piston.

It will be apparent that the broad principle of my invention is equally applicable to a long or short stroke riveter or other pneumatic implement, which may be manually or mechanically held, and that the same is applicable to other forms of rivet sets or other working tools than that shown. My novel device can be readily and cheaply manufactured, can be quickly attached to 80 and disconnected from the cylinder of the tool for the purpose of inspection and repairs, and will be found to be efficient and reliable in operation under all conditions. In case it is desired to renew or replace the 85 split ring 18, this can be quickly and expeditiously done upon the removal of the coupling sleeve, as is evident.

It will now be apparent that I have devised a novel and useful pneumatic hammer, 90 which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages. 100

Having thus described my invention, what I claim as new and desire to secure by Letters Patent, is:—

1. In a device of the character stated, a 110 rivet set having a shoulder thereon, a shank extending rearwardly from said shoulder and having a groove therein, a split ring engaging said groove, and a coupling sleeve adapted to be secured to a tool cylinder, said 115 coupling sleeve carrying said shank and having a chamber within which said split ring reciprocates, said split ring being adapted to slide over said rivet set shank to interlock with said groove, whereby the 120 shank of the rivet set when pushed into said cylinder will cause the ring to interlock with the groove, and whereby said rivet set can be removed from said coupling sleeve without removing the coupling sleeve from the 125 tool cylinder.

2. In a pneumatic hammer, the combination with a cylinder having at its forward end an aperture to receive a working tool and an enlarged chamber intermediate the 130

ends of said aperture forming a rear and a forward shoulder, of a working tool having its shank extending into said aperture and provided with an annular groove, and a 5 split ring detachably connected with the walls of said groove to reciprocate in unison with said shank within said chamber and to engage said forward shoulder to limit the outward travel of the working tool with respect to said cylinder, said split ring being 10 adapted to slide over said shank into locking position with said groove, whereby the working tool can be assembled with respect to said cylinder and removed therefrom by 15 relative longitudinal movement of the cylinder and working tool.

3. In a pneumatic hammer, a cylinder, a tubular sleeve connected to the forward end of said cylinder and apertured to receive the

shank of a working tool and provided with 20 a chamber of greater diameter than the diameter of said aperture, a working tool having its shank extending into said aperture, and a detachable member interlocked with said shank to move in unison with said 25 shank with the same length of stroke as the length of stroke of the working tool and to engage the forward wall of said chamber to prevent said working tool becoming disengaged from the pneumatic hammer, said 30 detachable member being adapted to slide over the shank of the working tool into its locked position when the working tool is inserted into the cylinder.
